UNITED STATES PATENT OFFICE.

PHILIP KLEEBERG, OF NEW YORK, N. Y.

DESIGN FOR EMBROIDERY.

SPECIFICATION forming part of Design No. 20,577, dated March 10, 1891.

Application filed February 13, 1891. Serial No. 381,362. Term of patent 3½ years.

To all whom it may concern:

Be it known that I, PHILIP KLEEBERG, a citizen of the United States, residing at New York city, in the county and State of New

5 York, have invented and produced a new and original Design for Embroidery, of which the following is a full, clear, and exact specification, reference being had to the accompanying drawing, forming a part thereof, which

10 represents a plan view of the design.

The design consists of a number of semi-circular connected figures *a*, grouped to simu-

late crescent figures *A*, and the crescent figures are represented as united by plume-like figures *B*, located at the horns of the crescent 15 figures.

I claim—

The design for embroidery, substantially as herein shown and described.

PHILIP KLEEBERG.
